SLING-SEATED FLOAT

Sidney A. Tarrson, 777 S. Tripp, Chicago, Ill. 60624

Filed Apr. 25, 1968, Ser. No. 11,621

Term of patent 14 years

Int. Cl. D21—03

U.S. Cl. D71—1

FIG. 1 is a perspective view of a sling-seated float, showing my new design;

FIG. 2 is a side elevational view thereof, the opposite side being substantially the same;

FIG. 3 is a bottom plan view thereof.

I claim:

The ornamental design for a sling-seated float, as shown and described.
